FUSE SWITCH

Charles Adin Fox, St. Louis, Mo., assignor to
 James R. Kearney Corporation, St. Louis, Mo.,
 a corporation of Missouri

Application May 20, 1935, Serial No. 22,408

17 Claims. (Cl. 200—122)

This invention relates generally to fuse switches, and more specifically to an improved fuse switch which, in addition to affording protection against short circuit faults in an electrical circuit with 5 which the fuse switch is associated, serves also, because of certain thermal means forming a part of the fuse switch, to afford maximum protection against overload faults in the circuit, the predominant object of the invention being to provide an improved fuse switch of this type which is capable of performing its intended function in 10 a highly efficient manner.

It is quite generally known to persons familiar with such matters that for a number of years it 15 has been the practice to protect distribution transformers of electrical systems through the use of fuse switches of various types. These fuse switches generally depend on opening the circuit by melting portions of the fuse elements, or by 20 melting soldered joints which hold parts of the fuse elements together. The melting of the fuse elements or the joints thereof takes place at certain predetermined current values and is dependent on the size and length of the fuse elements, the kind of wire thereof, and the melting 25 point of the wire constituting the fuse elements or the solder thereof. Owing to the fact that a fuse element is necessarily small, the temperature rise of the element follows very closely the current 30 rise in the circuit. The lag of the temperature curve of the fuse element behind the current curve of the circuit can be varied to some extent by changing the physical dimensions of the material, but essentially the fuse remains a quick 35 operating unit.

This characteristic makes the fuse ideal for short circuit protection (high current value faults), but naturally prevents it from having the necessary characteristics for overload protection. In order to prevent needless service interruptions from temporary overloads it is necessary, and has become general practice, to use a fuse element from two to five times the actual capacity 40 of the transformer. With the natural increase 45 in the use of electric service and the ever increasing number of electrical devices used, the load on the normal transformer is slowly creeping upward until finally the original excess capacity will have been exceeded, and unless there has 50 been considerable time spent in load checking or considerable outlay put in excess transformer capacity, or both, transformer loss is inevitable.

The improved device disclosed herein, which 55 may be described as a thermo-relay fuse switch, comprises a cartridge mechanism which may be

inserted in a standard switch mounting. It preserves the high quality short circuit protection of the fuse now in general use, and adds to this the ability to afford overload protection which the present fuse does not do. This combination 5 enables the excess transformer capacity to be reduced to a minimum, and also provides for the reduction to the minimum of the load survey cost.

Briefly stated, overload protection in the improved device is obtained by arranging a small heating element in series with the fuse element and interposing heat-insulating material between the heating element and a thermo-tripping element. The temperature of the thermo-tripping element can be made to lag behind the current flow in the heating element sufficiently long to care for all temporary load demands without interrupting the circuit by having the excess heat absorbed by adjacent parts of the switch structure, thus keeping the temperature of the thermo-tripping element below the tripping point. In the event, however, of the overload proving permanent, the temperature of the thermo-tripping element will continue to rise until the switch is 25 tripped out, thus protecting the transformer from injury caused by continued overload. The lag of the temperature of the thermo-tripping element behind the load current is controlled by the amount and character of the heat-insulating medium between the heating element and the thermo element, and somewhat by the construction of the assembly.

Fig. 1 is a side elevation of the improved fuse switch, parts of the switch mounting being broken 35 away to conserve space.

Fig. 2 is an enlarged section on line 2—2 of Fig. 1, with a part of the housing of the heating element broken away in order to show inner parts thereof.

Fig. 3 is a front elevation of the cartridge of the improved fuse switch.

Fig. 4 is an enlarged, fragmentary view, partly in vertical section and partly in elevation, of the lower portion of the cartridge of the improved 45 structure.

Fig. 5 is a vertical section on line 5—5 of Fig. 4.

Fig. 6 is a fragmentary, inverted, plan view of the cartridge as illustrated in Fig. 4.

Fig. 7 is a fragmentary, side elevation of the lower portion of the cartridge showing said portion as it appears when the thermo-tripping element has been actuated and dropping-out movement of the cartridge has started.

In the drawings, wherein is shown for the purpose of illustration, merely, one embodiment of the invention, A designates a standard switch mounting which includes an insulator B, upper and lower line terminals C and D secured to said insulator, upper and lower contact members E and F, and a bracket G by which the switch mounting is secured to a cross-arm or other element (not shown) by which it is supported. For the purpose of this disclosure, the upper contact member E may be considered to comprise a length of heavy wire fixed to the upper terminal and bent to provide a pair of substantially parallel, forwardly extended leg portions between which a portion of the cartridge of the improved structure is interposed for the purpose of providing mechanical and electrical connection between the cartridge and said upper contact member. The lower contact member F may be considered to comprise a forwardly extended member fixed to the lower terminal D and provided with laterally extended elements H which serve as hinge members for the cartridge of the improved structure.

Referring now to the cartridge of the improved fuse switch, I designates an expulsion tube formed of suitable insulating material or combinations of insulating materials. At its upper end the tube I is provided with a cap 2, which is in the form of a sleeve that embraces the upper end portion of the tube, said cap being pinned or otherwise secured to the tube and being provided with an upstanding finger 3 which is interposed between and is frictionally gripped by the outwardly extended, parallel legs of the upper contact member E when the cartridge is in the fusing position, for the purpose of mechanically and electrically connecting the upper end of the cartridge to the upper contact member E. At the top of the cap 2 an opening is provided which receives a head element 4 associated with a fuse element 5, said head element being seated against a face which surrounds the opening at the top of the cap 2 and having a portion 4' which extends a short distance downwardly into the tube I. The fuse element is attached to the head element 4 and is extended downwardly therefrom through the tube I in the usual manner. Also, the cap 2 is provided with a ring 6 which facilitates manual movement of the cartridge into and out of the fusing position with the aid of an insulated switch stick or fuse puller.

Fixed to the tube I of the cartridge at a point spaced upwardly from the lower end thereof is an arm 7, which includes a rearwardly extended portion 7' and a downwardly extended portion 8 provided at its opposite sides with ear portions 9. The rearwardly extended portion 7' and the downwardly extended portion 8 of the arm are preferably, though not necessarily, of substantially U-shaped cross-section, as shown in Fig. 2, and said arm 7 includes a collar portion 10 which fixedly embraces the tube I of the cartridge.

Pivotedly connected to the arm 7 is a hinge element 11, said pivotal connection between the arm and the hinge element being accomplished through the use of a pivot pin 12 which is extended transversely of the arm and the hinge element through apertures in the ear portions 9 of the arm and in portions 13 of the hinge element which are disposed between said ear portions (see Fig. 2). The hinge element 11 comprises spaced apart side portions 11a which are integrally connected by web portions 11b to provide a unitary structure, and also said hinge element includes an integrally formed, substantially circular plate por-

tion 14 which performs a function to be herein-after set forth. The spaced apart side portions of the hinge element 11a are provided with downwardly extended hook portions 15 which engage the laterally extended elements H of the switch mounting in a manner to cause the hinge element 11 to be hingedly supported by said laterally extended elements H, as shown in Figs. 1 and 7. The opposed side portions 11a of the hinge element 11 are provided also with hook portions 16 located above the hook portions 15, which are adapted to be engaged by an insulated switch stick when it is desired to detach the assembly comprised of the cartridge and the hinge element 11 from the switch mounting.

Fixedly supported by the plate portion 14 of the hinge element 11 is a thermal unit 17, which includes a tubular member 18 (Figs. 4 and 5). The tubular element 18 extends upwardly from the plate portion 14, as shown most clearly in Figs. 4 and 5, and said tubular element is surrounded in spaced relation relative thereto by a casing 19 of suitable insulating material. In the particular embodiment of the invention illustrated in the drawings, the casing 19 is circular in horizontal section and is seated at its lower end in an annular recess 20 formed in the plate portion 14 at the outer edge thereof. At the top of the casing 19 the thermal unit 17 includes a cap 21 which includes an upstanding, hollow portion 22 and an annular flange portion 23, the lower face of said flange portion being in contact with the top edge of the casing 19, and said flange portion being provided with an annular, downwardly extended portion 24 which embraces the upper portion of the casing, as shown in Figs. 4 and 5, so as to maintain the casing in its proper position relative to the cap 21.

At the upper end of the tubular member 18 a head 25 is provided which is recessed at its outer edge, as indicated at 26. The upper wall of the recess 26 is seated in contact with the top edge of the tubular member 18, and the lower portion of the head within the recess 26 is extended downwardly into the upper portion of the tubular member a short distance. Arranged immediately beneath the head 25 is a rod 27 which is fixedly seated at its opposite ends in alined apertures formed in the wall of the tubular member 18 and extends transversely through the hollow interior of the tubular member. The rod 27 has arranged in contact with its lower surface portion a more or less T-shaped element 28 which is provided with a depression or seat 28', the face of which contacts with the lower face of the rod. The upper, substantially horizontal portion of the T-shaped element 28 is provided with a pair of screw-threaded openings formed therethrough, through which adjusting screws 29 are extended, these adjusting screws passing also through alined apertures formed through the head 25. To the downwardly extended leg of the T-shaped element 28 a thermo-tripping element 30 is fixedly attached by means of suitable fastening means 30', said thermo-tripping element being provided at its lower end with a more or less hook-shaped portion 31. The cap 21 at the upper end of the thermal unit 17 is secured to the head 25 located at the top of tubular member 18 by a screw 32, which is extended through an opening formed through the top wall of the cap and is screwed into a screw-threaded opening formed in the head.

Pivotedly attached to spaced apart extensions 33 of the hinge element 11 (see Figs. 4 and 6) is a member 34 which includes a body portion 11

35 through which a pivot pin 36 is extended, said pivot pin being extended also through apertures formed through said spaced extensions 33. The member 34 includes a shaft 37 which is extended outwardly from the body portion 35, and this shaft rotatably supports a circumferentially grooved pulley 37' formed of insulating material about which, as will presently appear, the fuse element of the fuse switch passes. Extended upwardly and rearwardly from the body portion 35 of the member 34 is an extension 38, which is provided at its free end with a nose portion 39 having a flat underside 39', this flat face being adapted to be engaged by a flat face 40 at the outer end of the hook-shaped portion 31 of the thermo-tripping element 30 as shown most clearly in Fig. 4.

Arranged to surround the tubular member 18 of the thermal unit 17 is an elongated sleeve 41 formed of material characterized by the ability to act as a heat insulator as well as an electrical insulator. The sleeve 41 insulates from the tubular member 18 an electric heating coil 42, this heating coil being interposed between the sleeve 41 and the casing 19, which, as already stated herein, is formed of suitable electrical insulating material, fiber, for instance. One end of the wire which produces the heating coil 42 is attached, as shown most clearly in Fig. 2, to a connector 43 by means of a suitable fastening device 44, and the opposite end of said coil-producing wire is attached directly to the web portion 11b of the hinge element 11 by means of a suitable fastening device 45, as shown in Fig. 4. The connector 43 includes an outstanding, screw-threaded shank 46 (Figs. 1, 2, 3, and 7) at the base of which a disk 47 is located, and mounted on this shank is a wing-nut 48 which has a washer 49 associated with it. As is shown most clearly in Fig. 2, the fuse element 5 is electrically connected to the connector 43 by having a portion thereof turned about the shank portion 46 and clamped between the washer 49 and the disk 47.

When the cartridge is disposed in the fusing position, the fuse element 5 is held under constant tension, this by reason of the tendency of the hinge element 11 to turn about the pivot 12 resulting from forces set up by downward pressure exerted against the cartridge by the resilient upper contact E. When the fuse element becomes ruptured upon the occurrence of a short circuit, the hinge element 11, freed at its outer or fuse element engaging end and acting under the forces imparted thereto, turns rapidly about the two axes defined by the hinge members H and the pivot 12. Movement of the hinge element 11 about the hinge member H is accompanied by endwise lowering of the cartridge tube, which, when clear of the upper contact E, swings under action of gravity outwardly and downwardly to the full open position. It will appear that the hinge element 11 considered as a lever has a high velocity ratio and that its outer or fuse element engaging end moves very rapidly. Accordingly the ruptured ends of the fuse element become quickly separated, resulting in practically instantaneous extinguishment of the arc created therebetween.

When an overload fault causes the cartridge to drop out of the fusing position, the temperature of the thermo-tripping element 30 is increased because of the heat imparted thereto by the heating coil 42, and when the temperature

of said thermo-tripping element reaches the proper point, the lower hook-shaped end of said thermo-tripping element is tripped rearwardly. This tripping movement of the thermo-tripping element 30 frees the nose portion of the extension 38 of the member 34, thereby permitting the tensioned fuse element to move said member 34 about its pivot 36, the extension 38 swinging rearwardly and downwardly beneath the rearwardly displaced lower end of the thermo-tripping element and the pulley 37' moving with said extension to a tipped up position, where the fuse element may slip from the circumferential groove of said pulley, as shown by dotted lines in Fig. 7. This frees the fuse element engaging end of the hinge element 11 and permits said hinge element to turn rapidly about the two axes defined by the hinge members H and the pivot 12 so as to cause the cartridge to drop out of the fusing position, as already explained.

As heretofore explained herein, the temperature of the thermo-tripping element 30 is caused to lag behind the current flow in the heating element, so as to care for all temporary load demands without interrupting the circuit. This is accomplished by the use of the insulating sleeve 41 which is interposed between the thermo-tripping element and the heating coil 42. Therefore the heat produced by the heating coil, because of ordinary load demands on the circuit, is not sufficient to heat the thermo-tripping element to the tripping point because of the presence of the insulating sleeve. However, if an overload becomes permanent the temperature of the thermo-tripping element rises to the point where the thermo-tripping element is actuated and the cartridge immediately drops out of the fusing position, as described.

It is important to note that the thermo-tripping element 30 may be adjusted by manipulating the screws 29 so as to move the T-shaped element 28 in a rocking or pivotal manner relative to the rod 27. Thus the lower hook-shaped end of said thermo-tripping element may be positioned with respect to the nose portion 39 of the member 34 in a manner to regulate the point at which the nose portion of the member 34 will be freed from the restraint exerted thereupon by the lower end portion of the thermo-tripping element.

I claim:

1. A fuse switch comprising a switch mounting, a fuse cartridge adapted to be releasably supported by the switch mounting, means including an element adapted for movement in response to heat applied thereto for maintaining said fuse cartridge in the fusing position, and heat-producing means for releasing said cartridge for displacement from the fusing position by applying heat to said element of said cartridge-maintaining means.

2. A fuse switch comprising a switch mounting, a fuse cartridge adapted to be releasably supported by the switch mounting, means including a thermo-tripping element for maintaining said fuse cartridge in the fusing position, and means for releasing said cartridge for displacement from the fusing position, the last-mentioned means including an electrical heating element adapted to influence said thermo-tripping element.

3. A fuse switch comprising a switch mounting, a fuse cartridge adapted to be releasably supported by the switch mounting, a fuse ele-

- ment associated with said fuse cartridge, means including a thermo-tripping element for maintaining said cartridge in the fusing position, and means for releasing said cartridge for displacement from the fusing position, said means including an electrical heating element arranged in series with said fuse element and adapted to impart heat to said thermo-tripping element.
4. A fuse switch comprising a switch mounting, a fuse cartridge adapted to be releasably supported by the switch mounting, a fuse element associated with said fuse cartridge, means including a thermo-tripping element for maintaining said cartridge in the fusing position, means for releasing said cartridge for displacement from the fusing position, said means including an electrical heating element arranged in series with said fuse element and adapted to impart heat to said thermo-tripping element, and means for controlling passage of heat from said heating element to said thermo-tripping element.
5. A fuse switch comprising a switch mounting, a fuse cartridge adapted to be releasably supported by the switch mounting, a fuse element associated with said fuse cartridge, means including a thermo-tripping element for maintaining said cartridge in the fusing position, means for releasing said cartridge for displacement from the fusing position, said means including an electrical heating element arranged in series with said fuse element and adapted to impart heat to said thermo-tripping element, and insulating means for controlling passage of heat from said heating element to said thermo-tripping element.
6. A fuse switch comprising a switch mounting, a fuse cartridge adapted to be releasably supported by the switch mounting in the fusing position, a hinge element movably connected to said switch mounting and to said fuse cartridge and movable to release the fuse cartridge for displacement from the fusing position, heat-responsive means for maintaining said hinge element in position where the fuse cartridge is in the fusing position, and electrical heating means for causing said heat-responsive means to release said hinge element and permit the fuse cartridge to be displaced from the fusing position.
7. A fuse switch comprising a switch mounting, a fuse cartridge adapted to be releasably supported by the switch mounting in the fusing position, a hinge element pivotally connected to said switch mounting and to said fuse cartridge and movable to release the fuse cartridge for displacement from the fusing position, heat-responsive means for maintaining said hinge element in position where the fuse cartridge is in the fusing position, and electrical heating means for causing said heat-responsive means to release said hinge element and permit the fuse cartridge to be displaced from the fusing position.
8. A fuse switch comprising a switch mounting, a fuse cartridge adapted to be releasably supported by the switch mounting in the fusing position, a hinge element pivotally connected to said switch mounting and to said fuse cartridge and movable to release the fuse cartridge for displacement from the fusing position, heat-responsive means comprising a thermo-tripping element for maintaining said hinge element in position where the fuse cartridge is in the fusing position, and electrical heating means for causing said heat-responsive means to release said hinge element and permit the fuse cartridge to be displaced from the fusing position.

9. A fuse switch comprising a switch mounting, a fuse cartridge adapted to be releasably supported by the switch mounting in the fusing position, a hinge element pivotally connected to said switch mounting and to said fuse cartridge and movable to release the fuse cartridge for displacement from the fusing position, heat-responsive means comprising a thermo-tripping element for maintaining said hinge element in position where the fuse cartridge is in the fusing position, and electrical heating means for causing said heat-responsive means to release said hinge element and permit the fuse cartridge to be displaced from the fusing position, said thermo-tripping element and said electrical heating means being carried by said hinge element.

10. A fuse switch comprising a switch mounting, a fuse cartridge adapted to be releasably supported by the switch mounting in the fusing position, a fuse element associated with said fuse cartridge, a hinge element pivotally connected to said switch mounting and to said fuse cartridge and movable to release the fuse cartridge for displacement from the fusing position, said hinge element being engaged by said fuse element, heat-responsive means for maintaining said hinge element in position where the fuse cartridge is in the fusing position, and electrical heating means for causing said heat-responsive means to release said hinge element from said fuse element and permit the fuse cartridge to be displaced from the fusing position.

11. A fuse switch comprising a switch mounting, a fuse cartridge adapted to be releasably supported by the switch mounting in the fusing position, a fuse element associated with said fuse cartridge, a hinge element pivotally connected to said switch mounting and to said fuse cartridge and movable to release the fuse cartridge for displacement from the fusing position, said hinge element being engaged by said fuse element, heat-responsive means for maintaining said hinge element in position where the fuse cartridge is in the fusing position, and electrical heating means for causing said heat-responsive means to release said hinge element from said fuse element and permit the fuse cartridge to be displaced from the fusing position.

12. A fuse switch comprising a switch mounting, a fuse cartridge adapted to be releasably supported by the switch mounting in a fusing position, a fuse element associated with said fuse cartridge, a hinge element pivotally connected to said switch mounting and to said fuse cartridge and movable to release the fuse cartridge for displacement from the fusing position, movable means carried by said hinge means and engaged by said fuse element, heat-responsive means for engaging said movable means and maintaining said hinge element in position where the fuse cartridge is in the fusing position, and electrical heating means for causing said heat-responsive means to release said movable means for movement so as to permit the fuse element to be disengaged therefrom and permit the hinge element to move to displace the fuse cartridge from the fusing position.

13. A fuse cartridge provided with a fuse element and adapted to be releasably supported by a switch mounting, movable means associated with said fuse cartridge and engaged by the fuse element thereof and operable to release the fuse cartridge from the fusing position, restraining means

carried by said movable means for restraining movement of said movable means, and electrical heating means arranged to influence said restraining means in a manner to release said movable means for movement.

5 14. A fuse cartridge provided with a fuse element and adapted to be releasably supported by a switch mounting, movable means associated with said fuse cartridge and engaged by the fuse 10 element thereof and operable to release the fuse cartridge from the fusing position, restraining means carried by said movable means for restraining movement of said movable means, and electrical heating means carried by said movable 15 means and arranged to influence said restraining means in a manner to release said movable means for movement.

15. A fuse cartridge provided with a fuse element and adapted to be releasably supported by a switch mounting, movable means associated with said fuse cartridge and engaged by the fuse element thereof and operable to release the fuse cartridge from the fusing position, restraining means comprising a thermo-tripping element carried by said movable means for restraining movement of said movable means, and electrical heating means arranged to influence said restraining means in a manner to release said movable means for movement.

16. A fuse cartridge provided with a fuse element and adapted to be releasably supported by a switch mounting, movable means associated with said fuse cartridge and engaged by the fuse element thereof and operable to release the fuse cartridge from the fusing position, restraining means comprising a thermo-tripping element carried by said movable means for restraining movement of said movable means, electrical heating means arranged to influence said restraining means in a manner to release said movable means for movement, and means for manually adjusting the position of said thermo-tripping element.

17. A fuse cartridge provided with a fuse element and adapted to be releasably supported by a switch mounting, movable means associated with said fuse cartridge and engaged by the fuse element thereof and operable to release the fuse cartridge from the fusing position, restraining means comprising a thermo-tripping element carried by said movable means for restraining movement of said movable means, electrical heating means arranged to influence said restraining means in a manner to release said movable means for movement, and means including adjusting screws for manually adjusting the position of said thermo-tripping element.

CHARLES ADIN FOX.
